DEVICE FOR THREADING HAIRPINS OR THE
LIKE UPON CARDSWalter H. Hermsdorf, Chicago, Ill., assignor to
Chain Store Products Corporation, Chicago,
Ill., a corporation of Delaware

Application June 28, 1940, Serial No. 342,918

8 Claims. (Cl. 163—8)

This invention relates to improvements in a device for facilitating the mounting of hairpins, hair gripping fasteners and similar relatively thin members upon package or display cards.

Hairpins, hair gripping fasteners such as the so-called "Bobby Pins" and the like are frequently packed and merchandised upon cardboard cards. In most instances the cards are perforated to receive one or both legs of the article packed or displayed, and frequently the pins or other articles are mounted upon the cards in attractive artistic fashion. To thread hairpins or the like upon perforated cards is a manual operation and the labor cost bears a relatively high ratio to the total cost of the merchandised article.

My present invention contemplates a device which facilitates the manual operation of mounting the pins on the card by permitting the operator to use both hands in performing the task, the card being automatically distorted and held in such a manner as to greatly facilitate the threading operation.

The objects and advantages of my invention will be apparent from the accompanying drawings and following detailed description.

In the drawings,

Fig. 1 is a fragmentary side elevational view of a work table upon which the device comprising my invention may be mounted.

Fig. 2 is an enlarged top plan view of a fragmentary portion of the table illustrated in Fig. 1.

Fig. 3 is a sectional view taken on line 3—3 of Fig. 2.

Fig. 4 is a face view of a card carrying a plurality of hairpins threaded upon said card.

Fig. 5 is a fragmentary top plan enlarged view illustrating the manner in which the pins are guided into the apertures in the card.

Fig. 6 is a detail sectional view illustrating the manner of distorting the card.

Fig. 7 is a view similar to Fig. 6 illustrating a hairpin being threaded upon the distorted card.

Referring in detail to the drawings, 1 indicates a work table having top 2 supported by suitable legs 3. A plate 4 is secured to the lower surface of the top 2 by means of any suitable fastening devices (not shown). Intermediate the length of the plate a pair of spaced lugs 5 are formed, said lugs projecting downwardly from the plane of the plate 4. Lugs 5 are provided with apertures 6 which are disposed in alignment, the two lugs 5 serving as a yoke, the apertures 6 providing bearings for a pivot pin 7.

An aperture 8 is provided in the table top and

an arcuate portion 9 formed integral with plate 4 extends upwardly through said aperture, the upper face of the arcuate portion 9 being substantially flush with the upper surface of the table top.

The pivot pin 7 is transversely positioned upon an intermediate portion of lever 10, said lever being positioned between the lugs 5. One end of lever 10 carries a set screw 11, said set screw terminating in a hexagon head 12. A lock nut 13 is threaded upon the set screw 11 and serves to lock the set screw in a desired position. Adjacent the set screw 11 a plurality of recesses 14 are provided in lever 10, a coil spring 15 being positioned in each recess, said coil springs being confined between the base of the recesses 14 and the lower surface of the plate 4.

On the opposite side of the pivot pin 7 a set screw 16 is threaded into lever 10, said set screw 20 having a hexagon head 18 and carrying a lock nut 19 whereby the set screw can be locked in a desired position. Adjustment of the set screws 11 and 16 controls the arc through which the lever 10 can rock, the movement of the lever in a counter-clockwise direction being controlled by the set screw 16 and the movement of the lever in a clockwise direction being controlled by the position of set screw 11.

On that side of lever 10 which carries set screw 16, the lever is provided with an offset 19 which extends into a portion of the aperture 8. A circular disk 20 is carried upon a shoulder 21 of the offset portion 19 of the lever 10, the disk 20 being adapted to normally protrude through the aperture 8 to an elevation above the surface of the table top 2. The disk 20 is secured to the offset portion 19 of the lever by the means of machine screws 22 which are countersunk in the upper face of the disk 20.

A portion of the upper face of the disk 20 is provided with a substantially sectoral recess 23. Adjacent the circumference of the disk a segmental rib 24 is formed, said rib being provided with a plurality of radially extending slots 25, the slots being disposed adjacent each other throughout the arc traversed by the segmental rib.

A segmental element 26 is secured to the upper face of the arcuate member 9 by means of screws 27 or the like, the segmental element 26 conforming substantially in curvature with the arc of the member 9 and also being substantially concentric with the disk 20. The face of the segmental element 26 is provided with a plurality of radial grooves 28 which are disposed in

substantial registration or alignment with the radial grooves 25 provided in the rib 24.

An aperture 29 is provided in lever 10 and a link 30 is connected to said lever through said aperture. The link 30, at its opposite end, is connected to a pedal 31 pivoted as at 32 to member 33 mounted upon floor 34.

It can readily be seen that by manipulating pedal 31 lever 10 can be rocked about pivot 7 in a clockwise direction against the compressive force of springs 15. When the lever 10 is so rocked the disk 20 moves downwardly through aperture 8 until the surface of said disk lies appreciably below the surface of the table top. By releasing the force upon pedal 31, springs 15 act to rock lever 10 in a counter-clockwise direction, thus moving said lever until the foot of said screw 16 contacts the lower surface of plate 4. At this point in the travel of the lever the disk 20 will be in the approximate position shown in Fig. 3.

The disk 20 together with the corresponding segmental member 26 is adaptable to facilitate the threading of hairpins or the like upon a card such as card 35. The card 35 is provided with a plurality of apertures 36 which are disposed in an arc of a circle, said apertures being adjacent an edge of the card 35, said edge also defining an arc of a circle substantially concentric with the arc defined by the apertures 36. The card 35 is adapted to carry a plurality of hairpins 37 so mounted upon the card that the legs of the hairpins lie adjacent opposite faces of the card, and the U-bent portions of the hairpins are positioned in the apertures 36.

In utilizing my invention to facilitate the manual threading of the hairpins 37 upon the card 35, the following operation is carried out. Pedal 31 is depressed thereby rocking lever 10 in a clockwise direction causing disk 20 to move downwardly within aperture 8 in the table top. A pair of spaced guide pins 38 extend upwardly from the face of the disk 20 and are adapted to be engaged with apertures 39 provided in the card 35. By registering the pins 38 with the apertures 39 the arcuate portion of the card 35 will be disposed concentric with the center of the disk 20 and the apertures 36 will be interposed in alignment with the respective grooves 25 and 28. The radius of curvature of the arcuate edge of card 35 is slightly greater than the radius of curvature of the disk 20, and consequently the arcuate edge of card 35 overhangs the edge of the disk 20. The inner arcuate edge of the segment 26 has a radius of curvature slightly less than the radius of curvature of the arcuate edge of card 35. Accordingly, when card 35 is positioned upon the face of disk 20, the arcuate edge of said card will extend beyond the edge of the disk 20 and beneath the inner edge of the segmental element 26. With the card in this position the pedal 31 is released. Under the impulse of springs 15, lever 10 rocks in a counter-clockwise direction, thus confining that portion of the card 35 included between the arcuate edge of said card and the arc formed by the apertures 36. As shown best in Figs. 6 and 7, the lower surface of the segmental element 26 adjacent its inner edge is tapered as at 40. Hence, when the disk 20 moves upwardly under the impulse of springs 15, the card 35 is distorted, as shown best at 41 in Fig. 6. The distortion occurs substantially along the line defined by the apertures 36, thereby disposing the center lines of the respec-

tive apertures in alignment with the grooves 25 and 28.

In the usual hair-gripping fastener of the "Bobby pin" type, one leg of the pin is longer than the opposed leg, as indicated at 42 in Fig. 5. With the shorter leg uppermost the end of the lower leg may be positioned in one of the grooves 28, provided in the segmental element 26. The pin 37 may then be moved radially inwardly. The grooves 28 guide the longer end of the pin into an aperture 36, thus guiding the lower leg of the pin into contact with the rear surface of the card. The end of the upper leg of the pin is usually flared upwardly as shown at 43 in Fig. 7 and consequently, said upper leg slides along the upper surface of the card. In this manner the two legs of the pin 37 are caused to embrace opposite surfaces of the card. As radially inward motion of the pin continues the lower leg of the pin enters one of the grooves 25 and is guided and held in a radial position upon the card 36. The relationship of the two legs of the pin 37 with respect to the distorted card is clearly illustrated in Fig. 7.

It can readily be seen that with the card 35 clamped between the disk 20 and the segmental element 26 and prevented from moving laterally by the guide pins 38, both hands of the operator are free to move hairpins through the grooves 28 and into engagement with the card. Heretofore, it has been necessary for the operator to distort the card with one hand while inserting the pin into the aperture with the other. By the provision of my invention the card is distorted automatically thus bringing the apertures 36 into convenient position for the insertion of a pin 37.

It is to be understood, of course, that any number of arrangements of pins may be utilized merely by changing the shape of the cards and by changing the shape of the disk 20 and guide member 26. If desired, the grooves in the segmental member 26 may be eliminated entirely and still some of the benefits of my invention will be obtained. Similarly, it is not essential that a groove 25 in the rib 24 be provided for each pin since only a sufficient number of upwardly extending portions, that is, division walls between adjacent grooves, be provided to clamp the card into contact with the lower overhanging edge of the member 26. Broadly, my invention contemplates a convenient means for distorting a card along the line defined by a plurality of apertures so as to dispose the axes of said apertures in a plane which approaches a parallel relationship to the plane of the card. The provision, however, of the grooved member 26 is preferable since it facilitates location of the end of the lower leg of the hairpin into the aperture.

A boss 44, extends above the surface of the disk 20 whereby an intermediate portion of the card 35 when in position upon said disk is raised a relatively short distance above the surface of the disk. The boss 44 is preferably so located upon the disk 20 as to be adjacent an edge of the card whereby said edge may be gripped by the hand in removing the card from the disk. However, when the card is filled with pins the pedal 31 is depressed and due to the fact that a portion of the edge of the card is raised above the surface of the disk the operator can conveniently remove the card from the disk. In view of the fact that the boss 44 tends to raise an intermediate portion of the card, a leaf spring 45 is preferably secured as by rivets 46 to a por-

tion of the segmental member 26, said spring functioning to prevent the arcuate edge of the card from being lifted excessively by the boss 44. If said leaf spring were not provided, the lifting of an intermediate portion of the card by the boss 44, due to the resiliency of the card, would cause the edge of the card which is to be confined beneath the overhanging portion 49 to extend above the surface of the segmental member 26, thus causing inconvenience in properly clamping the card.

I claim as my invention:

1. A device for facilitating the threading of one leg of a hairpin-like article through an aperture in a relatively flat card constructed of bendable material which comprises, two adjacent members relatively movable in shears fashion with respect to each other, means for mounting an apertured card upon one of said members with the major portion of said card co-planar with said member and with said aperture adjacent the line of shear between said members, means for moving said members in shears fashion whereby the card is distorted to dispose a portion of the defining edge of said aperture in the plane of the major portion of the card and another portion of said edge in a plane oblique to the plane of the major portion of the card.

2. A device for facilitating the threading of one leg of a hairpin-like article through an aperture in a relatively flat card constructed of bendable material which comprises two adjacent members relatively movable in shears fashion with respect to each other, along a single line of shear only, means for mounting an apertured card upon one of said members in substantially co-planar position with respect to said member and with said aperture adjacent the line of shear between said members, means for moving said members in shears fashion whereby the card is distorted to dispose the axis of said aperture at an angle less than ninety degrees with respect to the plane of the major portion of the card and with a portion of an edge defining said aperture substantially in the plane of the major portion of the card, and means carried by one of said members for guiding an end of said hairpin-like article into said aperture.

3. A device for facilitating the threading of one leg of a hairpin-like article through an aperture in a relatively flat card constructed of bendable material which comprises two adjacent members relatively movable in shears fashion with respect to each other, along a substantially single line of shear only, means for mounting an apertured card upon one of said members with said aperture adjacent the line of shear between said members, means for moving said members in shears fashion whereby the card is distorted along a substantially single line of shear only to dispose the axis of said aperture at an angle less than ninety degrees with respect to the plane of the major portion of the card, means carried by one of said members for guiding an end of said hairpin-like article into said aperture, and means carried by the other member for guiding said hairpin-like article to a predetermined position upon said card during the threading of the article through the aperture.

4. A device for facilitating the threading of one leg each of a plurality of hairpin-like articles through aligned apertures provided in a relatively flat card constructed of bendable material which comprises, two adjacent members relatively movable in shears fashion, the adjacent

edges of said members conforming with the alignment of said apertures in said card, means for mounting said apertured card upon one of said members with the major portion of said card co-planar with said member and with said aligned apertures adjacent the line of shear between said edges, means for moving said members in shears fashion to distort a portion of said card and dispose a portion only of the defining edges of each of said apertures in the plane of the major portion of said card.

5. A device for facilitating the threading of one leg each of a plurality of hairpin-like articles through aligned apertures provided in a relatively flat card constructed of bendable material which comprises, two adjacent members relatively movable in shears fashion, along a substantially single line of shear only, the adjacent edges of said members conforming with the alignment of the apertures in said card, means for mounting said apertured card in a predetermined position upon one of said members with said aligned apertures adjacent the line of shear between said edges, means for moving said members in shears fashion to distort said card along said substantially single line of shear and dispose the axes of said apertures at an angle less than ninety degrees with respect to the plane of the major portion of said card, and means carried by one of said members for guiding an end of said hairpin-like articles into said apertures, the apertures in said card when the card is in predetermined position being in substantial alignment with said guiding means.

6. A device for facilitating the threading of one leg each of a plurality of hairpin-like articles through aligned apertures provided in a relatively flat card constructed of bendable material which comprises, two adjacent members relatively movable in shears fashion, along a substantially single line of shear only, the adjacent edges of said members conforming with the alignment of the apertures in said card, means for mounting said apertured card upon one of said members with said aligned apertures adjacent the line of shear between said edges, means for moving said members in shears fashion to distort said card and dispose the axes of said apertures at an angle less than ninety degrees with respect to the plane of the major portion of said card, means carried by one of said members for guiding an end of said hairpin-like articles into said apertures, and means carried by the other member for guiding said hairpin-like articles to predetermined positions upon said card during the threading of the articles through the apertures.

7. A device for facilitating the threading of one leg each of a plurality of hairpins through arcuately aligned apertures provided in a relatively flat card constructed of bendable material which comprises, two adjacent members relatively movable in shears fashion, along a substantially single line of shear only, the adjacent edges of said members being arcuate in conformity with the aligned apertures in said card, means for mounting said apertured card upon one of said members with the plane of said card substantially parallel with the plane of said members and with said aligned apertures adjacent the line of shear between said edges, means for moving said members in shears fashion to distort said card and dispose opposite portions of the defining edges of said apertures in different planes, one of said defining edge portions being the

plane of that portion of the card which is disposed on said supporting shear member.

8. A device for facilitating the threading of a hairpin-like article through an aperture in a relatively flat card constructed of bendable material which comprises two adjacent members relatively movable in substantially shears fashion with respect to each other, means for mounting an apertured card upon one of said members in substantially plane-parallel relationship with said member and with said aperture adjacent

the line of shear between said members, means for moving one of said members in substantially shears fashion to distort a portion of the card adjacent said aperture to dispose a portion only of the defining edge of the aperture in substantially the plane of the major portion of the card, whereby a hairpin-like article may be threaded into said aperture along substantially the plane of the major portion of the card.

10
